UNITED STATES PATENT OFFICE.

SIMON GOLDNER AND LOUI GOTTLIEB, OF NEW YORK, N. Y.

DESIGN FOR A RING FOR CLUSTER-SETTINGS.

SPECIFICATION forming part of Design No. 34,857, dated July 30, 1901.

Application filed June 25, 1901. Serial No. 66,010. Term of patent 7 years.

To all whom it may concern:

Be it known that we, SIMON GOLDNER, a citizen of the United States, and LOUI GOTTLIEB, a subject of the Czar of Russia, both residing at New York, borough of Manhattan, in the State of New York, have invented and produced a new and original Design for Rings for Cluster-Settings, of which the following is a specification, reference being had to the accompanying drawings, in which—

Figure 1 is a side elevation showing our design, and Fig. 2 is a plan view of the same.

The leading or material features of our design for a ring for a cluster-setting are the general elliptic contour of the segmental portion, the inverted serrate-dentate ornamentation at the border of the segmental portion, and the doubly-scalloped configuration at the edge of the segmental portion.

A indicates a ring-shaped body, and B the segmental projecting portion forming the

cluster-setting proper. This segmental portion B is of a general elliptic form and is provided with an inverted serrate-dentate border ornamentation C, in which the dentils are closely disposed. The edge of the top surface of the segmental portion B is doubly scalloped, and the said surface is provided with three ellipses D, and a series of small circles E near the edge surrounding said ellipses. 30

What we claim as new is—

The design for a ring for a cluster-setting substantially as shown and described.

In testimony that we claim the foregoing as our invention we have signed our names in presence of two subscribing witnesses.

SIMON GOLDNER.
LOUI GOTTLIEB.
